Primary Examiner — Susan Bennett Hattan

Assistant Examiner — Landon Thomas Cassell

(57) **CLAIM**

The ornamental design for a massage gun, as shown and described.

DESCRIPTION

FIG. 1 is a front elevational view of a massage gun showing my new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.

The broken lines in the drawings illustrate portions of the massage gun that form no part of the claimed design.
